UNITED STATES PATENT OFFICE.

FRANK J. MUHLFELD, OF NEW YORK, N. Y.

MANUFACTURE OF ONE-PIECE FELT HATS.

No. 899,887.

Specification of Letters Patent.

Patented Sept. 29, 1908.

Application filed April 4, 1908. Serial No. 425,090.

To all whom it may concern:

Be it known that I, FRANK J. MUHLFELD, a citizen of the United States, residing at No. 770 East One Hundred and Seventy-fifth street, New York, county of New York, and State of New York, have invented certain new and useful Improvements in the Manufacture of One-Piece Felt Hats, fully described and represented in the following 10 specification and the accompanying drawings, forming a part of the same.

The object of this invention is to facilitate the manufacture of a one-piece felt hat with a brim and a head-opening smaller than that 15 portion of the crown adjacent to the brim, and the invention consists in first blocking the body, including the felt intended for the brim, into a general cylindrical shape and, in the upper part, of the diameter desired for 20 the finished crown, then supporting such upper part upon a hat-block of the shape and size desired for the entire finished crown, clamping the edge of the body, and contracting the portion between the bottom of said 25 crown and such edge into a band of the size desired for the head-opening, and then working such head-band up to the bottom of the crown and expanding the edge of the body into the form desired for the brim.

30 This process may be employed with hat-blocks of different shapes, whether round, oval, perpendicular to form a vertical crown, or slanting to form an oblique crown; but in all cases it produces a fold which extends inwardly from the base of the crown to the head-opening and thence outwardly into the brim. This fold forms a narrow flat channel between the crown and the inner portion of the brim next the head-opening, which is 35 characteristic of the invention. The adjacent walls of this channel may, if desired, be secured together by cement, stitching, or otherwise, so as to make the crown set close upon the upper surface of the brim, or they 40 may be unsecured, leaving the body of the crown raised slightly, that is by the width of the channel, above the brim.

The product of the process which is described may be the same as that claimed in 50 my Patent No. 796,923 dated August 8, 1905, and I have not, therefore, claimed such a product herein; but the present invention is also capable of producing a different article for which I have made specific claims. 55 The process of my present invention is the exact opposite of that employed in the said

patent, only the first step, namely, the blocking of the hat-body, being the same as both processes, but the crown in the patented process being expanded above the 60 head-band which is formed by the hat-block.

In the present process the hat-body is blocked in the commencement to the final size desired and neither requires or receives any subsequent expansion, and it is only the 65 head-band which is produced by the subsequent treatment, and such treatment is the reverse of expansion, as it consists in contracting the felt below the hat-block to the size desired. The product of the present 70 invention also differs from those hats in which the lower part of the crown is contracted to form a so-called bell-crowned hat, as such bell-crowned hats commonly have the head-opening of the same size as the bottom of the crown, which in bell-crowned hats slopes from the upper part of the crown directly to the brim at the band, which is coincident with the head-opening.

In the present invention, the bottom of 80 the crown, which corresponds with the band of previous constructions, is not of the same size as the head-opening, but is connected therewith by a flat annular portion of the felt, which is extended inwardly from the bottom 85 of the crown to the head-opening, upon the upper side of the fold which forms the head-opening.

The invention may be applied to hats having crowns and brims of any desired form, 90 provided a smaller head-opening is desired than the bottom portion of the crown, and it entirely supersedes the necessity of using reducers for the head-opening, such as are shown in my Patent No. 769,558 dated September 6, 1904.

The invention will be understood by reference to the annexed drawing, in which

Figure 1 is a diagram showing the conical hat-body; Fig. 2 the body stretched upon a 100 hat-block into a general cylindrical shape; Fig. 3 the edge of the body clamped and the portion intermediate to such edge and the bottom of the hat-block contracted at the middle of its height to the size desired for 105 the head-opening; Fig. 4 shows the contracted portion worked up to the bottom of the hat-block and the felt below the same stretched partially outward to form the brim; Fig. 5 shows the head-band held in shape 110 while the brim is drawn flat or parallel with the bottom of the head-block; and Fig. 6

shows the finished product. Fig. 7 is a vertical section of the finished product with the crown brought close to the brim; and Fig. 8 is an edge view of a hat with an oblique 5 crown and the brim curved by flanging. Figs. 9 and 10 are views similar to Figs 3. and 10 4 showing the clamps applied to the edge of the felt to clamp it during the different steps of the process; Figs. 11 to 13 inclusive show 15 the divided ring for working the felt inwardly or contracting it below the bottom of the crown; Fig. 11 showing the opposite parts of the rings separated to place about the felt; Fig. 12 showing the opposite parts joined and the felt contracted; and Fig. 13 showing an edge view.

a designates the hat-body in Fig. 1, b the hat-block in Fig. 2 upon which the body a is shown blocked to a general cylindrical shape, 20 with the edge c of the felt bent outwardly to be held during such operation.

In Fig. 3, the felt between the bottom of the hat-block b and the edge c is contracted, as by a thin divided ring d, into the size desired for the head-band, such contraction necessitating the approximation of the block b to the edge c of the body as the felt is contracted.

Figs. 9 and 10 show clamps c' for clamping the edge c of the body during the process; the block b being shown mounted upon a spindle b' by which it can be raised or lowered as may be desired, to approximate the block to the edge of the body. The divided ring may be made of any suitable construction, one form being shown in Figs. 11 and 13 with two opposite side sections d' having a separable joint, as a snap-button d² at their outer ends, to connect and disconnect them, and having their opposite ends connected by a jointed link d³ and a hand-lever d⁴. When the ends d² are connected, as shown in Fig. 12, and the hand-lever thrown over the adjacent side section, the ring has 45 a circular form; but when the hand lever is thrown outward and the snap-button is disconnected, the ring may be widely opened to place around the hat-body a below the hat-block. In connecting the free ends of the 50 side sections, the felt is then crumpled inside of the ring, but the working of the ring up and down, and the manipulation of the felt by the hands or by a suitable slicker, operates to work out the wrinkles and to contract the felt to the desired shape.

Fig. 4 shows the ring worked up to the bottom of the hat-block, thus forming the head-band at the bottom of the crown, and the body-portion a' below such ring stretched 60 partly into the form of the brim, requiring the block and the edge c to be yet more closely approximated, which is readily effected by lowering the block in the desired degree by means of its spindle b'.

Fig. 5 shows the portion a' stretched into

the flat brim f parallel with the bottom of the crown, the bottom of the block and the edge of the brim being brought to the same level in this final step of the process, and the ring d serving to hold the band in place during the 70 stretching of the brim. The clamps c' are in practice constructed to slide outwardly for thus stretching the brim; but the clamps are not claimed herein. The hat-block b is retained within the crown until the hat is 75 finished, and is made, as is common in such constructions, of sections which can be withdrawn successively from the contracted aperture of the head-band. Such hat-blocks are used in all hat manufacture where the 80 head-opening is smaller than the crown.

Fig. 6 shows the finished product with crown e having a fold g extended inward from its base to the head-opening h, forming a narrow flat channel i between the bottom 85 of the crown and the brim f. Where desired, the adjacent walls of this channel may be readily secured together by cement or stitching so as to make the bottom of the crown set close to the brim, as shown in Fig. 7. 90

Fig. 8 is an external view of the hat having an oblique crown with the channel open between the base of the crown and the brim, and the brim curved upward and downward at opposite edges by any ordinary means. 95 The illustration in Fig. 8 is introduced merely to show that the invention is not limited to straight crowns or brims.

By the use of sectional hat-blocks and flanges of suitable shape, the crown and hat 100 may be finished in any desired style; but always possesses the channel g either open as shown in Figs. 6 and 8, or closed as shown in Fig. 7, as a characteristic of its manufacture.

I am aware that hats have been blocked 105 upon a block provided with a flange to support the brim of a hat, such block having a shallow groove or crease around the base of the crown to form a "break" between the base of the crown and the brim of the hat. 110 Such "break" does not furnish a crown with a head-opening materially smaller than that portion of the crown adjacent to the brim, as the shallow groove in the hat block is not sufficient to form a flat channel having flat 115 sides between the brim and the bottom of the crown at their junction. Such flat channel can only be formed by the process described herein, and the article which I have claimed herein is therefore materially different from that in Wilkinson's patent, which shows no process like mine.

Having thus set forth the nature of the invention what is claimed herein is:

1. The process of manufacturing a one-piece felt hat with a brim and having a head-opening smaller than that portion of the crown adjacent to the brim, which consists in first blocking the body including the felt intended for the brim into a general cylind- 130

drical shape and of the size desired for the finished crown, second, supporting the upper part of such body in the shape desired for the entire crown, and clamping the edge of the body, and third, contracting the felt close to the bottom of the crown to the size desired for the head-band and expanding the felt below such contracted portion into the form desired for the brim.

10 2. The process of manufacturing a one-piece felt hat with a brim and having a head-opening smaller than that portion of the crown adjacent to the brim, which consists in first blocking the body including the felt intended for the brim into a general cylindrical shape and of the size desired for the finished crown, second, supporting the upper part of such body in the shape desired for the entire crown, clamping the edge of the body, and contracting the portion between the bottom of said crown and such edge into a band of the size desired for the head-opening, and third, working such contracted portion or head-band up to the bottom of the crown 25 and expanding the edge of the body into the form desired for the brim.

3. The process of manufacturing a one-piece felt hat with a brim and having a head-opening smaller than that portion of the crown adjacent to the brim, which consists in first blocking the body including the felt intended for the brim into a general cylindrical shape and of the size desired for the finished crown, second, supporting the upper 30 part of such body in the shape desired for the entire crown, and clamping the edge of the body, and third, working the felt adjacent to the bottom of the crown into a flat narrow groove to form the contracted head-opening, 35 and simultaneously expanding the felt below such groove to form a brim adjacent to the lower side of such groove.

4. The process of manufacturing a one-

piece felt hat with a brim and having a head-opening smaller than that portion of the 45 crown adjacent to the brim, which consists in first blocking the body including the felt intended for the brim into a general cylindrical shape and of the size desired for the finished crown, supporting the upper part of 50 such body by means adapted to shape the entire crown, clamping the edge of the body and gradually contracting into a band of the size desired for the head-opening the felt between the bottom of said crown and such 55 edge, and simultaneously lowering the support for the crown to the level of the said edge and expanding the felt below such contracted band into the form desired for the brim, and producing a narrow flat groove 60 between the brim and the bottom of the crown.

5. As a new article of manufacture, a one-piece felt hat having a crown and brim with head-opening smaller than that portion of 65 the crown adjacent to the brim, with a narrow flat channel between the brim and bottom of the crown at their junction such channel having parallel sides.

6. As a new article of manufacture, a one-piece felt hat having a crown and brim with head-opening smaller than that portion of the crown adjacent to the brim, with a narrow flat channel between the brim and the bottom of the crown at their junction, such 75 channel having parallel sides and the adjacent walls of the said channel secured together to close the channel and hold the bottom of the crown close to the brim.

In testimony whereof I have hereunto set 80 my hand in the presence of two subscribing witnesses.

FRANK J. MUHLFELD.
